UNITED STATES PATENT OFFICE.

PEPPINO MAJORANA, OF LOUISVILLE, KENTUCKY.

RAIL-JOINT.

1,293,496.

Specification of Letters Patent.

Patented Feb. 4, 1919.

Application filed May 16, 1918. Serial No. 234,964.

To all whom it may concern:

Be it known that I, PEPPINO MAJORANA, a subject of the King of Italy, residing at Louisville, in the county of Jefferson and State of Kentucky, have invented new and useful Improvements in Rail-Joints, of which the following is a specification.

This invention relates to rail joints, and one object of the invention is to provide a novel construction of lapping rail ends whereby a continuous and unbroken rail connection will be afforded at the joint, to make the rails solid at the joint and to keep the rail ends in alignment with each other.

15 A further object of the invention is to provide a joint in which the rail ends are so formed and connected as to enable the use of fish plates to be dispensed with, while permitting proper expansion and contraction, and wherein provision is also made to prevent depression or spreading of the rail ends and the hammering, due to wear and tear, in the passage of wheels over the joint, in the use of rails of ordinary construction.

25 With these and other objects in view, the invention consists of the features of construction, combination and arrangements of parts, hereinafter fully described and claimed, reference being had to the accompanying drawing, in which:—

Figure 1 is a side elevation of two connected rails, showing a construction of joint embodying my invention.

Fig. 2 is a vertical longitudinal section of the same.

Fig. 3 is a vertical transverse section on line 3—3 of Fig. 1.

Fig. 4 is a view in end elevation of one of the rail ends.

40 Fig. 5 is a perspective view of the same.

Fig. 6 is a perspective view of the other rail end.

Referring to the drawing, 1 and 2 designate adjoining rails, the ends whereof are constructed to provide the improved joint, each rail in general being of ordinary construction and comprising a base 3, head 4 and connecting web 5.

50 The rail member 1 has its base 3 cut away for a determined distance inwardly from its end, and adjacent to the end of its base has

its web 5 provided with a laterally expanded or thickened portion 6, from which projects a tongue 7. The tongue 7 is of less width than the portion 6 but of greater width than the web 5 and terminates at its outer end flush with the end of the head 4.

As shown, the tongue 7 is in the form of an oblong rectangular bar integral with the base of the head 4 and having straight and vertical outer end and side portions, the bottom surface of said tongue terminating in a plane above the bottom of the expanded portion 6; whereby side and bottom shoulders or abutment portions 8 and 9 are formed at the outer extremity of said expanded portion. The base of the expanded portion 6 projects in advance of the end 10 of the base 3 in the form of a transverse ledge 11, for a purpose hereinafter described. Formed upon the underside of the tongue 7 is a series of V-shaped or tapered lugs 12, and formed in the tongue 7 adjacent to the ends thereof are transverse bolt holes 13.

The rail member 2 has its head 4 shortened or cut away inwardly for a distance from its end substantially equivalent to the length of the tongue 7, and this rail member has its web 5 expanded laterally, as shown at 14. The expanded portion 14 is of a width approximately equal to or slightly less than the width of the head 4 and is integral with the base 3 of said rail member. The outer end of the expanded portion 14 projects beyond the shortened head a distance equal to the length of the tongue 7 and is bifurcated to provide a pair of spaced plates 15 forming an intervening groove 16 to receive the tongue 7 when the rail members are properly joined together. The upper edges of the plates 15 terminate in line with the bottom of the head 4 and the groove 16 is made of less depth than the depth of the web 5 so as to increase the thickness of the base 3 beyond the head of the rail.

When the rail ends are united, the tongue 7 fits snugly in the groove 16 with the ends of the heads 4 abutting and the outer end of the tongue bearing against the expanded end of the web 5 of the rail member 2, the base of the tongue resting upon the thickened bottom of the groove 16, whereby abutment sur-

faces of increased size are afforded to increase the strength of the rail ends at the joint. When so connected the rail ends will also be firmly supported against depression and lateral movement, since the upper edges of the plates 15 will bear against the overhanging flanges of the head 4 of the rail member 1, and the thickened webs will strengthen and reinforce the rail ends in wardly of and on opposite sides of and beyond the joint, the plates 15 serving the function of fish plates and thus doing away with the necessity of employing separate fish plates, whereby a solid joint is produced which is absolutely rigid and avoids the use of independent parts, thereby increasing the stability of the joint and affording security in the passage of the wheels of rolling stock over the rails.

20 The thickened bottom wall 17 of the groove 16 is formed with tapered sockets or recesses 18 to receive the lugs or projections 12 on the tongue, whereby the rail ends are connected against longitudinal displacement, and the plates 15 are formed with bolt holes 19 to register with the bolt holes 13 in the tongue, said bolt holes being adapted for the passage of bolts 20, whereby the rail ends are retained in position against upward vertical displacement. In practice, owing to the great strength of the joint, it will ordinarily not be found necessary to employ more than two bolts, since no strain falls upon these fastenings, so that weakening of the parts by the use of a greater number of bolt holes will be avoided.

40 The base 17 of the rail member 2 projects beyond the outer ends of the plates 15 in the form of a projecting ledge 21 having a beveled or inclined surface 22, which ledge is adapted to extend under the portion 11 of the rail member 1 and with the surface 22 abutting against the inclined surface 10 of said rail member 1, thus additionally supporting the ends of the rails to give increased strength in the region of the joint. The surfaces 8 and 9 of the rail member 1 are adapted to abut against the outer end edges 23 of the plates 15, the contacting surfaces being preferably beveled or obliquely disposed to lie at an angle to the vertical and thus additionally support the rail ends against any possibility of depression.

50 It will be evident from the foregoing description that the invention provides a joint formed solely by portions of the rail ends, with the exception of the retaining bolts, and that such portions perform the functions of fish plates and other independent parts commonly used, thus simplifying the construction and avoiding the use of independent parts liable to cause trouble and which weaken the joint. It will also be evident that by expanding the portions as de-

scribed joint members of maximum width and thickness are produced to brace the rail ends and sustain the weight and pressure of the wheels of the rolling stock, thus making the joint absolutely solid and rigid against displacement and avoiding hammering and other stresses and noises due to wear and tear and play of the rail ends under the pressure of the rolling stock in the use of joints and rails of ordinary construction. 75

It will, of course, be understood that the bolt holes and interengaging surfaces may be so formed as to permit sufficient relative movement of the rail ends to compensate for expansion and contraction; also that the details of construction may be varied as desired, within the scope of the appended claims, without departing from the spirit or sacrificing any of the advantages of the invention. 85

Having thus fully described my invention, I claim:—

1. A rail joint comprising a rail member having a thickened web projecting beyond its head and cut away to provide spaced plates forming a groove, said groove being of less depth than the body of the web and forming a base of increased thickness, the outer ends of the plates being beveled and said base having a portion extending beyond 90 said plates in the form of a ledge provided with a terminal beveled surface, a second rail member having a head projecting upon its base and a thickened web projecting beyond the base and continuing in the form of 95 a tongue of a length to fit within the aforesaid groove, the outer end of the body of the thickened portion of the web being projected beyond the base of the rail member and coöperating therewith to form inclined 100 abutment surfaces engaging the edges of the plates and ledge of the base of the first named rail member, the base of the tongue and bottom wall of the groove being provided with interengaging surfaces, and transverse bolts connecting the plates and tongue to hold the rail ends against relative vertical displacement. 105

2. A rail joint comprising a rail member having a thickened web projecting beyond 115 its head and cut away to provide spaced plates forming a groove, said groove being of less depth than the body of the web and forming a base of increased thickness, the outer ends of the plates being beveled and said base having a portion extending beyond 120 said plates in the form of a ledge provided with a terminal beveled surface, the said bottom wall of the groove being formed with tapered transverse recesses, and a second rail member having a head projecting beyond its base and a thickened web projecting beyond the base and continuing in the form of a tongue of a length to fit within the aforesaid groove, the outer end of the 125 130

body of the thickened portion of the web being projected beyond the base of the rail member and coöperating therewith to form inclined abutment surfaces engaging the 5 edges of the plates and ledge of the base of the first named rail member, said tongue being provided on its under side with tapered

transverse lugs to engage said transverse recesses, and transverse bolts connecting the plates and tongue to hold the rail ends 10 against relative vertical displacement.

In testimony whereof I affix my signature.

PEPPINO MAJORANA.
